DESIGN.

A. PETZOLD.

RUG.

No. 16,177.

Patented July 21, 1885.

UNITED STATES PATENT OFFICE.

ADOLPH PETZOLD, OF PHILADELPHIA, PENNSYLVANIA.

DESIGN FOR A RUG.

SPECIFICATION forming part of Design No. 16,177, dated July 21, 1885.

Application filed April 11, 1885. Term of patent 3½ years.

To all whom it may concern:

Be it known that I, ADOLPH PETZOLD, a citizen of the United States, and a resident of Philadelphia, Pennsylvania, have invented and 5 produced a new and original Design for a Rug, of which the following is a specification, reference being had to the accompanying photographic illustration, to which reference is made.

The accompanying illustration represents 10 my rug with one of the end panels omitted, as the latter will be a duplicate of the one shown.

The design consists of an outer broad border, a central or middle panel, and two end panels. At each of the two long edges of the middle 15 panel is a narrow strip or inner border, hereinafter more fully described. A half-rosette, with side scrolls, ornaments the middle of the upper one of these strips, and a fanciful flower the middle of the lower one. Both strips are 20 ornamented with small right-angled figures. Each end panel contains the representation of a lady with a little child by her side, both in Japanese or Chinese costume. The middle panel contains, also, the pictures of two striped 25 curtains, each partially rolled up askew or crooked. The spaces between the stripes in each are ornamented with vines and flowers. The stripes themselves are decorated with small figures resembling crosses, each sur- 30 rounded by a pattern closely approximating a diamond in appearance. The broad border is ornamented near its outer edge with a continuous line of arches, and near its inner edge with a line of blocks.

35 A is the outer broad border; B, the central panel; C, one of the end panels; D D', the two narrow strips above referred to; E, a half-

rosette in the middle of strip D; F, a large fanciful flower in the middle of strip D'. G represents a lady in Japanese or Chinese costume, and H the child, similarly attired; I J, the pictures of two partly-rolled-up curtains in the central panel, B; K K K, the stripes in the curtains; L L L, the vines or twigs between the stripes; M M, the flowers on the vines or twigs; N N, the small cross-shaped figures on the stripes; O O, the patterns surrounding figures N N, closely approximating diamond shapes, (see illustration;) P P, the line of arches on the broad border; R R, the blocks near the 40 inner edge of the same. S S is an elevated board walk or pathway, represented as sustained by supports T T from the ground below.

The leading features of my design are the external border, A, central panel, B, ornamented with the partially-rolled-up curtains, and the end panels, C, containing the representation of a lady with a little child by her side, both in Japanese or Chinese costume, 55 all these leading features being ornamented with smaller figures, substantially as shown. The terms "Japanese" or "Chinese" are not used in the sense of being alternatives, but because the costumes of the ladies of those two nations are of the same type, bearing a general resemblance one to the other.

What I claim as new is—

The design for rugs, substantially as shown and described.

ADOLPH PETZOLD.
